UNITED STATES PATENT OFFICE.

MAGDALENE HOMAN KROPÉ, OF NEW YORK, N. Y.

DESIGN FOR A FINGER-RING.

53,040.

Specification for Design.

Patented Mar. 4, 1919.

Application filed October 5, 1917. Serial No. 194,989. Term of patent 3½ years.

To all whom it may concern:

Be it known that I, MAGDALENE HOMAN KROPÉ, a citizen of the United States, residing at New York, in the county of New York and State of New York, have invented a new, original, and ornamental Design for Finger-Rings, of which the following is a specification, reference being had to the accompanying drawings, forming part thereof.

Figure 1 is a front elevation of a finger-ring, showing my new design; and Fig. 2 is a plan view thereof.

I claim:

The ornamental design for a finger-ring, as shown.

MAGDALENE HOMAN KROPÉ.
